US0D1081639S

(12) **United States Design Patent** (10) **Patent No.:** **US D1,081,639 S**
(45) **Date of Patent:** **** Jul. 1, 2025**

(54) **PORTABLE ELECTRONIC DEVICE CASE**

(71) Applicant: **Alo Beauty Corp**, Encino, CA (US)

(72) Inventors: **Rachel C. Levin**, Los Angeles, CA (US); **Zachary T. A. Aldridge**, Los Angeles, CA (US); **Aren A. Kaser**, Seattle, WA (US); **Joshua Buesseler**, Seattle, WA (US)

(73) Assignee: **Alo Beauty Corp**, Encino, CA (US)

(**) Term: **15 Years**

(21) Appl. No.: **29/884,772**

(22) Filed: **Feb. 15, 2023**

(51) LOC (15) Cl. **14-03**

(52) U.S. Cl.

USPC **D14/250**

(57) **CLAIM**

The ornamental design for a portable electronic device case, as shown and described.

DESCRIPTION

FIG. 1 is a top, front, right-side perspective view of a portable electronic device case, showing our new design; FIG. 2 is a bottom, front, left-side perspective view thereof; FIG. 3 is a top, rear, right-side perspective view thereof; FIG. 4 is a bottom, rear, left-side perspective view thereof; FIG. 5 is a front elevational view thereof; FIG. 6 is a rear elevational view thereof; FIG. 7 is a left-side elevational view thereof; FIG. 8 is a right-side elevational view thereof; FIG. 9 is a top plan view thereof; FIG. 10 is a bottom plan view thereof; and, FIG. 11 is a top, front, right-side perspective view thereof wherein the portable electronic device case is shown with an environmental cell phone.

The broken lines in FIGS. 1-11 are for the purpose of illustrating portions of the portable electronic device case, and environmental structure, that form no part of the claimed design.

1 Claim, 9 Drawing Sheets
